UNITED STATES PATENT OFFICE.

JACOB L. KLEINMAN, OF NEW YORK, N. Y.

TOP.

Application filed July 28, 1926. Serial No. 125,344.

This invention relates generally to improvements in tops and more particularly to improvements in the pegs thereof.

The primary object of the present invention is to provide a top that will absorb the shocks and strains caused by the impact against the ground when the top is thrown thereon for spinning purposes.

A further object is to provide a top that will skip or dance during its spinning operation.

A further object is to provide a top with a peg that is yieldingly mounted so as to lessen the likelihood of breaking the top and peg when it strikes the ground.

A still further object is to provide a top that is simple in construction and economical to manufacture.

With these and other objects in view to be hereinafter described, the invention consists in the novel features of construction and in the arrangement and combination of parts to be hereinafter described and particularly pointed out in the subjoined claims.

25 In the drawing, Figure 1 is a side elevation of a top partly in section provided with a peg embodying my invention.

Figure 2 is an enlarged detail view of a modified form of peg.

30 Figure 3 is an enlarged detail view of another modified form of peg.

Figure 4 is a view of the lower part of a top partly in section and partly in elevation showing still another form of peg construction.

35 Figure 5 is a view similar to Figure 4 but illustrating a modified form of peg construction not shown in the other views.

Referring to the drawing in detail, Figure 1 illustrates a preferred form of peg construction. In this figure, the top body 10 is formed of wood as usual and is conical in shape. In the lower body portion is provided a central bore 11 and said lower body portion terminates in a base 12, the surface of which slants upwardly towards its center.

40 Mounted snugly in this bore 11 is a peg 13. This peg 13 in the drawing is illustrated as made of rubber, but it will be understood that it may be made of any yielding material. The said peg 13 comprises an upper cylindrical body portion and a lower conical body portion 14, the outer periphery 45 of said conical body portion 14 conforming to the outer contour of the body of the top

when the peg is fitted in its bore. Between the upper cylindrical body portion and the lower conical body portion 14 is a reduced portion 15, which provides a space or chamber 16 for a purpose which will be explained. The conical body portion 14 has its lower surface dished out as indicated at 17, and its upper surface dished out as indicated at 17'. Formed in the center of the peg 13 is an elongated cylindrical opening 18, which opening 18 terminates in a slightly curved portion 19.

50 Fitted into the opening 18 of the peg 13 is a metal peg constructed with a cylindrical stem 20, a bulge or flange portion 21 slightly larger than the curved portion 19 and a conical portion 22, which latter portion 22 terminates in an outwardly flared portion 23. Formed in the conical portion 22 is a central bore 24 provided with a shoulder 25. As will be noted from Figure 1, the cylindrical stem 20 does not extend to the roof of the opening 18 but leaves a space between said roof and the upper surface of said stem 20. 55 This stem is also not sufficiently large to fill the said opening 18 and consequently a space 26 is provided between it and the inner wall of the rubber peg 13. The conical portion 22 has its upper surface dished out so as to leave a space 27 between said upper surface and the lower dished surface of the conical portion 14 of the rubber peg 13.

55 Into the bore 24 of the metal peg is loosely mounted a metal spindle. This spindle comprises a cylindrical body portion 28, the lower end of which is formed with a rounded surface for spinning upon any suitable surface; a collar or flange 29, the said spindle terminating at its upper end in an inwardly flared portion with a flat upper surface which is adapted to engage the flat roof provided by the bore 24. It will be noted that the collar 29 is not sufficiently large to engage the inner wall of the conical section 22 of the metal peg thereby leaving a space surrounding said collar to permit the spindle to spin freely in the bore 24. A space is also provided between the upper surface of the spindle and the roof of the bore 24 so as to permit the spindle to move upwardly when the top is thrown to the ground. The shoulder 25 formed on the conical section 22 engages the collar 29 and thus prevents the spindle from falling out of its position.

60 It will be obvious that the space 16 sur-

rounding the reduced portion 15 of the rubber peg 13 permits the rubber peg at that point to expand and the space between the inner wall of said reduced portion 15 and 5 the cylindrical stem 20 of the metal peg permits the rubber peg 13 to contract, when it is thrown against the ground for spinning purposes. It will also be apparent that the space between the upper end of the stem 20 10 of the metal peg and the roof of the opening 18 permits a longitudinal upward movement of said metal peg but this upward movement is controlled by the suction formed in the space between the base 12 and the dished 15 upper surface of the conical section 14 of the peg 13 and by the suction formed in the space 27 between the lower dished surface of the conical section 14 of the rubber peg 13 and the upper dished surface of the conical 20 section 22 of the metal peg.

The rubber peg illustrated in Figure 2 comprises an upper cylindrical portion 30, a reduced portion 31, a conical portion 32 which is substantially the length of the reduced portion 31 terminating at its lower end in outwardly flared portion 33. The upper surface of the conical portion 32 is dished out as indicated at 34.

Formed in the center of the conical portion 32 and extending to substantially the upper end thereof is a bore 35, which bore is restricted by means of an annular flange 36 formed on the interior periphery of the conical section 32. Fitted into this opening 35 is a metal peg comprising an upper cylindrical portion 37 provided with a rounded upper surface, an intermediate restricted portion 38 and a lower cylindrical portion 39 formed with a flat base. This lower cylindrical portion 39 is provided with a central bore 40 which extends upwardly to a point substantially to the top of the said portion 39, and downwardly to a point adjacent the lowermost end of the portion 39. Formed in the base of said portion 39 and 45 concentric with the bore 40 and communicating with latter bore 40 is another bore of smaller diameter, forming a shoulder or inwardly extending flange 41 on the lower portion 39.

Mounted loosely in the bores 40 and 41 is a metal spindle provided with an elongated collar 42 having a flat upper surface and a cylindrical body portion 43 formed 55 with a rounded lower surface for spinning purposes. It will be noted that the diameter of the collar 42 is not as large as the diameter of the bore 40, thus leaving a space between the collar and the inner wall of the portion 39 to permit the spindle to spin freely in the bore 40. It will also be noted that the collar 42 engages the shoulder 41 formed on the portion 39 and prevents the spindle from falling out of the bore. By reason of this 60 construction, a space is provided between

the upper surface of the cylindrical portion 37 and the roof of the bore 35 to permit upward longitudinal movement of the metal peg, and it will be understood of course that the annular flange 36 engages the restricted 70 portion 38 of the metal peg thereby preventing the metal peg from falling out of the opening 35 and any longitudinal movement of said peg is against the action of the annular flange 36.

In the form of the invention illustrated in Figure 3, the rubber peg disclosed is similar to the rubber peg shown in Figure 1 and consists of the upper cylindrical portion 13, the lower conical portion 14 and the restricted portion 15, the lower conical portion 14 being provided with upper and lower dished out surfaces. A central bore 44 is formed in the restricted portion and the conical section but is however formed uniform throughout its length and is not restricted at any point as is the opening 18. Into this central bore 44 is snugly fitted a metal peg comprising an elongated stem 45 formed uniformly throughout its length, 90 which when in operative position as shown in Figure 3 extends to a point below the roof of the bore 44 leaving a space between the top of the peg and the said roof to permit longitudinal movement of the metal peg as will be understood. In this form of peg construction, the stem 45 is forced into the bore 44 and tightly engages the wall of the bore 44 to prevent the peg from falling out.

With reference to Figure 4, the form here disclosed shows a metal peg somewhat similar in construction to the metal peg illustrated in Figure 3 and comprises an elongated cylindrical stem 46 which is adapted to be fitted snugly into the bore 11 of the top body. Disposed between the base 12 of the body 10 of the top and the dished out surface of the conical section 22 of the metal peg is a rubber washer 46 formed with a flat upper and lower surface. When this washer 46 is in operative position as illustrated in Figure 4, a space 47 is provided between said washer and the conical section 22, and a space 48 between said washer and the base 12 of the body 10 of the top. This washer 46 absorbs the shocks caused by throwing the top to the ground.

Referring to Figure 5, in this modification of the invention, it will be noted that the top body 10 is formed with a central bore 49, having a diameter larger than the diameter of the stem 45 of the metal peg which extends into the same, thereby leaving a space between said stem 45 and the inner wall of the top body 10. Surrounding the stem 45 and extending to a point about midway the length of the same is a rubber sleeve 50 and formed integrally with said rubber sleeve 50 is an annular flange 51, the said washer 51 being pro-

vided with dished upper and lower surfaces and being disposed between the base of the body 10 of the top and the upper surface of the conical section 22.

5 While I have illustrated and described several embodiments of my invention, I desire it to be understood that minor changes may be made in the construction and arrangement of the parts without departing 10 from the spirit of the invention and I desire to be limited only by the state of the prior art and the appended claims.

I claim:

1. A top comprising a body portion having a centrally disposed opening therein, a peg mounted in said opening, a spinning member loosely mounted in said peg and shock absorbing means operatively connected to said body portion, and peg.

20 2. A top comprising a body portion having a centrally disposed opening therein, a peg mounted in said opening, and a spinning member loosely mounted in said peg and means to permit said peg and said spinning member to yield when the top is thrown to the ground for spinning.

3. A top comprising a body portion having a centrally disposed opening therein, a rubber peg engaging said body portion, said rubber peg having an opening, a metal peg mounted in said openings, and a spindle mounted loosely in said metal peg, said metal peg being adapted to move relative to said rubber peg.

35 4. A top comprising a body portion having a centrally disposed opening therein, cushioning means engaging said body portion, a metal peg engaging said cushioning means, a spindle loosely mounted in said metal peg and means to prevent said metal peg from becoming detached from said cushioning means.

5. A top comprising a body portion having a centrally disposed opening therein, a rubber peg mounted in said opening, said rubber peg having a centrally disposed bore, a metal peg mounted in said latter bore, a spindle mounted loosely in said metal peg, said latter bore formed with an enlarged portion, and an annular flange formed on the metal peg adapted to engage the enlarged portion of the bore to prevent the metal peg from falling out of the same.

6. A top comprising a body portion having a centrally disposed opening therein, a slanting base formed on the bottom of said body portion, a rubber peg mounted snugly in said opening, said rubber peg consisting of an upper cylindrical section, an intermediate restricted section and a conical section, said conical section formed with dished out upper and lower surfaces, a central bore formed in said restricted and conical sections, said bore formed with an enlarged portion adjacent its lower end, a metal peg

mounted in said latter bore, said metal peg comprising a stem, a concial section and an annular flange formed on said stem, said conical section formed with upper and lower dished out surfaces, and a spindle mounted 70 loosely in said metal peg, said rubber peg and metal peg being so positioned that the dished out surfaces of their conical sections are adjacent each other to permit relative movement between said pegs.

7. A top comprising a body portion, yielding means mounted within said body portion, said yielding means having a reduced portion and a dished surface, means formed on said yielding means to hold said yielding 80 means in said body portion permitting said reduced portion and dished surface to expand and a peg mounted within said yielding means.

8. A top comprising a body portion, yielding means mounted within said body portion, said yielding means having a reduced portion and a dished surface and a centrally disposed opening, means formed on said yielding means to hold same in said body portion permitting said reduced portion and dished surface to expand, a peg mounted 90 within said opening and means formed on said yielding means to hold said peg and spread said opening.

9. A top comprising a body portion, yielding means mounted within said body portion, said yielding means having a reduced portion, a dished surface and a centrally disposed opening, means formed on said yielding means to hold same in said body portion permitting said reduced portion and dished surface to expand, a peg mounted within said opening and means formed on 100 said peg adapted to hold said peg in said yielding means and spread said opening at said point of engagement.

10. A top comprising a body portion, yielding means mounted within said body portion, said yielding means having a reduced portion, a dished surface and a centrally disposed opening, means formed on said yielding means to hold same in said body portion permitting said reduced portion and dished surface to expand, a peg 110 mounted within said opening and means formed on said yielding means and on said peg to hold said peg within said yielding means.

11. A top comprising a body portion, 120 yielding means mounted within said body portion, said yielding means having a reduced portion and a centrally disposed opening, means formed on said yielding means to hold the same in said body portion permitting said reduced portion to expand, a peg mounted within said opening forming a chamber between said yielding means and said peg and means formed on said yielding means to hold said peg.

12. A top comprising a body portion, yielding means mounted within said body portion, said yielding means having a reduced portion and a centrally disposed opening, means formed on said yielding means to hold the same in said body portion permitting the reduced portion to expand, a peg mounted within said opening, means formed on said peg to hold said peg in said yielding means and spread said opening at the point of engagement and spread said opening and chambers formed between said yielding means and body portion and between said yielding means and said peg.
13. A top comprising a body portion, yielding means mounted within said body portion, said yielding means having an

elongated centrally disposed opening therein, a peg mounted within said opening, said peg comprising enlarged and reduced portions, the size of said reduced portion being smaller than the size of said opening.

14. A top comprising a body portion, yielding means mounted within said body portion, said yielding means having an elongated centrally disposed opening therein, a peg mounted within said opening, said peg comprising enlarged and reduced portions, the diameter and length of said reduced portion being smaller than the diameter and length of said opening.

In testimony whereof, I hereunto affix my signature.

JACOB L. KLEINMAN.
